US00D724866S

(12) United States Design Patent (10) Patent No.: US D724,866 S
Johnson et al. (45) Date of Patent: * Mar. 24, 2015

(54) MATTRESS COVER

(71) Applicants: Kara W. Johnson, San Francisco, CA (US); Elger Oberwelz, San Francisco, CA (US); Thomas D. C. Overthun, San Francisco, CA (US); Thomas Brisebras, San Francisco, CA (US); Mihoko Ouchi, Oakland, CA (US)

(72) Inventors: Kara W. Johnson, San Francisco, CA (US); Elger Oberwelz, San Francisco, CA (US); Thomas D. C. Overthun, San Francisco, CA (US); Thomas Brisebras, San Francisco, CA (US); Mihoko Ouchi, Oakland, CA (US)

(73) Assignee: Tempur-Pedic Management, LLC, Lexington, KY (US)

() Term: 14 Years

(21) Appl. No.: 29/478,132

(22) Filed: Dec. 31, 2013

(51) LOC (10) Cl. 06-09

(52) U.S. Cl.

USPC D6/606; D6/596; D5/62

(58) Field of Classification Search

USPC D6/305, 382, 383, 391, 392, 393, 394, D6/395, 406.6, 583, 595, 596, 601, 602, D6/603, 604, 605, 606, 607, 622, 690, D6/718.31; D5/7, 37, 39, 48, 53, 55, 56, D5/57, 58, 60, 61, 62, 63, 66; 5/500, 501, 5/502, 626, 646, 647, 655, 665, 668, 675, 5/677, 689, 690, 691, 693, 696, 698, 700, 5/702, 703, 705, 706, 709; 112/117, 176, 112/401, 416, 418, 439; 138/418; 428/138, 428/187, 141; 442/59, 308; 2/244
